UNITED STATES PATENT OFFICE.

LUTHER L. KNOX, OF BELLEVUE, PENNSYLVANIA, ASSIGNOR TO BLAW-KNOX COMPANY, OF PITTSBURGH, PENNSYLVANIA, A CORPORATION OF NEW JERSEY.

WATER-COOLER FOR FURNACES.

1,371,906.

Specification of Letters Patent. Patented Mar. 15, 1921.

Application filed April 3, 1918. Serial No. 226,405.

To all whom it may concern:

Be it known that I, LUTHER L. KNOX, a citizen of the United States, residing at Bellevue, in the county of Allegheny and State of Pennsylvania, have invented a new and useful Improvement in Water-Coolers for Furnaces, of which the following is a full, clear, and exact description, reference being had to the accompanying drawings, 10 forming part of this specification, in which:

Figure 1 is a transverse vertical section of a furnace having my invention applied thereto.

Fig. 2 is a side elevation of a portion of 15 the furnace.

Fig. 3 is an enlarged section of a furnace wall having one of my coolers embedded therein.

Fig. 4 is a side view of the cooler, showing 20 a slight modification, and

Fig. 5 is a sectional view of the cooler shown in Fig. 4.

My invention has relation to wall coolers 25 for furnaces and is designed to provide a simple and efficient form of cooler which can be readily placed in the wall of the furnace to be cooled.

Referring to the accompanying drawings, the numeral 2 designates the side walls 30 of the furnace and the opposite sides of the hearth 3 to which I have shown my improved coolers applied. I desire it understood, however, that the invention is not limited to the use of any particular type of 35 furnace.

Each of the coolers consists of a hollow sheet metal body of general rectangular form and of any desired dimensions. If desired, the dimensions can be arranged with 40 respect to the dimensions of the bricks used in constructing a furnace wall so as to facilitate the setting of the coolers in the wall. The coolers are designed to set substantially flush with the outer surface of the wall, 45 their outer sides being flat, while their inner faces are longitudinally recessed, as indicated at 4, thereby forming the upper and lower projections 5 which extend into the furnace wall to a greater depth than the recessed 50 portion. The cooler can be conveniently made of an outer flat sheet or plate 6, and an inner sheet or plate 7, the latter being bent and shaped to form the recess and projections, its edge portion being welded to 55 the edges of the plates 6, as indicated at 7.

8 designates a water inlet connection having an arm 9 extending downwardly to a point near the bottom of the cooler, at one end portion thereof. 10 is an outlet connection at the top, near the opposite end portion of the cooler, the adjacent upper wall of the cooler being preferably somewhat raised at this point so as to permit the outlet to be placed at a sufficiently high point to prevent the formation of steam pockets within the 60 cooler. 11 designates a suitable plugged washout opening, or connection.

Where the coolers are made in relatively large sizes, they may be provided with any suitable internal bracers and reinforcing 70 means, such means being indicated at 12 in Fig. 4 and one of them being shown in detail in Fig. 5, and being generally of the character described and claimed in my Patent No. 1,168,647. Any other suitable 75 interior bracing means may, however, be employed.

A plurality of the coolers may be placed end to end in the wall to be cooled, as shown in Fig. 2. While I have shown only one 80 row of tiers of the coolers in this figure, it will be understood that more than one row of tiers can be employed if desired.

The longitudinally recessed form of the inner faces of the coolers enables them to 85 be readily bonded into the wall. This form also enables the employment of a sufficiently large body of cooling fluid within the wall, without unduly weakening the wall. It also very materially increases the area of cooling 90 surface in contact with the furnace wall.

I claim:

1. The combination with a vertically extending furnace wall, of a cooler therefor, consisting of a hollow metal structure having water-circulating connections, and set into the outer portion of the said wall, said structure having a substantially flat outer surface, but having a plurality of hollow horizontally extending ribs projecting from 100 its inner surface into the body of the wall, and receiving portions of the wall between them, substantially as described.

2. The combination with a vertically extending furnace wall, of a cooler therefor, consisting of a hollow metal structure having water-circulating connections, and set into the outer portion of the said wall, said structure having a substantially flat outer surface, but having a hollow horizontally ex- 110

tending rib projecting into the wall from both its upper and lower edge portions, and receiving a portion of the wall between them, said ribs terminating short of the inner surface of the wall, substantially as described.

3. The combination with a vertically extending furnace wall, of a cooler therefor, consisting of a hollow metal structure having water-circulating connections, and set into the outer portion of the said wall, said structure having a substantially flat outer

surface, but having a hollow horizontally extending rib projecting into the wall from both its upper and lower edge portions, and receiving a portion of the wall between them, said ribs terminating short of the inner surface of the wall, said cooler occupying a zone which extends upwardly from a point near the hearth of the furnace, substantially as described.

In testimony whereof, I have hereunto set my hand.

LUTHER L. KNOX.
